UNITED STATES PATENT OFFICE.

HUBERT R. HUMPHREY, OF KALAMAZOO, MICHIGAN, ASSIGNOR TO GENERAL GAS LIGHT COMPANY, OF KALAMAZOO, MICHIGAN.

GAS HEATER.

Application filed February 2, 1922. Serial No. 533,652.

To all whom it may concern:

Be it known that I, HUBERT R. HUMPHREY, a citizen of the United States, residing at Kalamazoo, county of Kalamazoo, State of Michigan, have invented certain new and useful Improvements in Gas Heaters, of which the following is a specification.

This invention relates to improvements in gas heaters.

The main object of this invention is to provide an improved gas heater in which the burner may be adjusted into operative position in the heater or withdrawn therefrom as an operative unit for purposes of demonstration, adjustment and the like.

Further objects, and objects pertaining to details and economies of construction and operation will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawings forming a part of this application in which:

Fig. I is a front elevation of my improved gas heater with parts broken away to show structural details, the burner being shown in operative position in the frame by full lines and in its retracted position by dotted lines.

Fig. II is a detail rear elevation.

Fig. III is an enlarged detail vertical section on a line corresponding to line 3—3 of Fig. I.

Fig. IV is a detail horizontal section on a line corresponding to line 4—4 of Fig. I showing details of the positioning stop within the frame.

Fig. V is a detail vertical section on a line corresponding to line 5—5 of Fig. III showing the relation of the burner to other parts when adjusted to operative position within the frame.

In the drawings the sectional views are taken looking in the direction of the little arrows at the ends of the section lines and

similar numerals of reference refer to similar parts throughout the several views.

Referring to the drawings, 1 represents the main casing-like housing and 2 a supporting plate mounted therein. 3 is the fireback arranged upon the supporting plate and 4 are the tubular foraminous radiating elements arranged upon the supporting plate in front of the fireback and in alignment with the openings 5 of the supporting plate.

I provide a burner which, in the structure illustrated, comprises a plurality of burner tubes 6 having burner tips 7 adapted to deliver through the openings 5 into the bases of the radiating elements 4. The burner body is preferably an integral casting.

The manifold 8 is provided with a plurality of nozzles 9 delivering to the lower end of the burner tubes 6, the general structure of the burner being preferably that shown in the patent to A. H. Humphrey, No. 1,245,347, dated November 6, 1917. The manifold carries a gas valve designated generally by the numeral 10. The burner is slidably supported on the spaced ways 11, the burner body being arranged between these ways and supported thereon by the pins 12 extending transversely of the burner body and riding upon the top of the ways. The outer ends of the ways are supported by the leg 13.

A stop 14 is provided within the frame to coact with the inner end of the burner body 85 positioning the burner with its tips in alignment with the holes 5. A handle 15 is provided for retracting and pushing the burner into the frame. The gas supply connection 16 is flexible so that the burners 90 are operative when adjusted into the frame or withdrawn therefrom, thus enabling inspection and tests of the flame or other tests of the burner and adjustment thereof when retracted and also the demonstration of its 95 operation and efficiency in operative relation to the fireback and radiating elements of the heater.

My improvements are especially designed by me for the purpose of demonstrating and 100 exhibiting gas heaters of this artificial fuel type and I have illustrated my improve-

ments as I have embodied them in practice. My improvements are, however, adaptable and desirable for use in other relations and I desire to be understood as claiming them broadly within the scope of the appended claims as well as specifically in the embodiment illustrated.

Having thus described my invention what I claim as new and desire to secure by Letters Patent is:

1. In a gas heater, the combination of a frame, a supporting plate mounted therein and provided with a plurality of burner openings, a fireback mounted on said supporting plate, foraminous tubular radiating elements disposed on said supporting plate in front of said fireback and in alinement with the openings of said supporting plate, a burner comprising a burner body having a plurality of burner tubes provided with tips adapted to be alined with the openings of said burner plate, a gas manifold provided with a plurality of gas nozzles coacting with said burner tubes, a gas valve carried by said manifold, and spaced slideways between which said burner body is slidably supported mounted with one projecting at one end of said frame so that the burner may be adjusted to a position within the frame with its tips in alinement with the burner openings or withdrawn from the frame as a complete operative unit independently of said radiating elements.

2. In a gas heater, the combination of a frame, a supporting plate mounted therein and provided with a plurality of burner openings, a fireback mounted on said supporting plate, foraminous tubular radiating elements disposed on said supporting plate in front of said fireback and in alinement with the openings of said supporting plate, a burner comprising a burner body having a plurality of burner tubes provided with tips adapted to be alined with the openings of said burner plate, a gas manifold provided with a plurality of gas nozzles coacting with said burner tubes, and a support on which said burner is slidably supported so that it may be adjusted to a position within the frame with its tips in alinement with the burner openings or withdrawn from the frame as a complete operative unit independently of said radiating elements.

3. In a gas heater, the combination of a frame, a fireback mounted within said frame, radiating elements disposed in front of said fireback, a burner comprising a burner body having a plurality of burner tubes provided with tips adapted to be alined with the radiating elements, a gas manifold provided with a plurality of gas nozzles coacting with said burner tubes, and spaced slideways between which said burner body is slidably supported, said ways projecting at one end of said frame so that the burner may be

adjusted to a position within the frame with its tips alined with the radiating elements or withdrawn from the frame as a complete operative unit independently of said radiating elements.

4. In a gas heater, the combination of a frame, a fireback mounted within said frame, radiating elements disposed in front of said fireback, a burner comprising a burner body having a plurality of burner tubes provided with tips adapted to be alined with the radiating elements, a gas manifold provided with a plurality of gas nozzles coacting with said burner tubes, and a support on which said burner is slidably supported so that it may be adjusted to a position within the frame with its tips alined with the radiating elements or withdrawn from the frame as a complete operative unit independently of said radiating elements.

5. In a structure of the class described, the combination of a heater body comprising a frame, a fireback and a plurality of tubular foraminous radiating elements disposed in front of said fireback, a burner comprising a plurality of burner tubes provided with tips, a manifold provided with nozzles operatively associated with said burner tubes, said manifold being provided with a control valve, a way on which said burner is slidably mounted so that it may be adjusted into the frame and into operative relation to said radiating elements or withdrawn therefrom and supported on said way as an operative unit independently of said radiating elements, and a stop for positioning said burner within said frame.

6. In a structure of the class described, the combination of a heater body comprising a frame, a fireback and a plurality of tubular foraminous radiating elements disposed in front of said fireback, a burner comprising a plurality of burner tubes provided with tips, a manifold provided with nozzles operatively associated with said burner tubes, said manifold being provided with a control valve, and a way on which said burner is slidably mounted so that it may be adjusted into the frame and into operative relation to said radiating elements or withdrawn therefrom and supported on said way as an operative unit independently of said radiating elements.

7. In a structure of the class described, the combination of a heater body comprising a frame, a fireback and a plurality of tubular foraminous radiating elements disposed in front of said fireback, a burner provided with a plurality of burner tips, a way on which said burner is slidably mounted so that it may be adjusted into the frame and into operative relation to said radiating elements or withdrawn on and supported by said way as an operative unit independently of said radiating elements, and a stop for

positioning said burner within said frame.

8. In a structure of the class described, the combination of a heater body comprising a frame, a fireback and a plurality of tubular 5 foraminous radiating elements disposed in front of said fireback, a burner provided with a plurality of burner tips, and a way on which said burner is slidably mounted so that it may be adjusted into the frame and 10 into operative relation to said radiating elements or withdrawn on and supported by said way as an operative unit independently of said radiating elements.

9. In a structure of the class described, the combination of a heater comprising a frame, 15 radiating elements supported by said frame, a burner, and a support on which said burner is slidably mounted to be adjusted in operative relation to said radiating elements or to be retracted from said frame as an operative 20 burner unit independently of said radiating elements.

In witness whereof, I have hereunto set my hand and seal.

HUBERT R. HUMPHREY. [L.S.]
